UNITED STATES PATENT OFFICE.

HARLIE O. PUTT, OF ELKHART, INDIANA, ASSIGNOR TO ANDREW H. BEARDSLEY, OF ELKHART, INDIANA.

IMPULSER FOR MAGNETOS.

1,326,529.

Specification of Letters Patent. Patented Dec. 30, 1919.

Application filed December 9, 1918. Serial No. 265,873.

To all whom it may concern:

Be it known that I, HARLIE O. PUTT, a citizen of the United States, residing at Elkhart, in the county of Elkhart and State of Indiana, have invented a new and useful Impulser for Magnetos, of which the following is a specification.

The object of my invention is to provide a novel improved cushioning device for cushioning the winding disk or stud in an impulser, to cause the armature of an ignition magneto to be actuated very quickly by means of a single coil spring which is compressed within a circular shell or housing. 10 It is further my object to provide a novel winding disk having a single stud in operative engagement with the coil spring, and to provide an improved arrangement of dogs and trips to control the periodic action of 15 the impulser. It is an especial object of my invention to obtain the greatest possible cushioning effect, and to eliminate pounding shock and vibration as far as possible, and thus increase the life and efficiency of 20 the instrument by utilizing the maximum winding space and the maximum length of 25 spring.

In former devices in this art arrangements of springs have been provided which 30 effect a sudden stop of the impulse of the mechanism as well as the armature of the magneto to which it is attached, which proves very destructive to the life and efficiency of those members, and which it is the purpose 35 of my invention to obviate.

Referring to the accompanying drawings illustrating my invention:—

Figure 1 is an elevational view of my invention applied to a magneto;

40 Fig. 2 is a vertical section of my impulser;

Fig. 3 is an elevational view of the drive end of the impulser;

Fig. 4 is a transverse section on line 4—4 45 of Fig. 2;

Fig. 5 is a transverse section on line 5—5 of Fig. 2;

Fig. 6 is a transverse section on line 6—6 of Fig. 2;

50 Fig. 7 is a detail elevational view of the winding disk;

Fig. 8 is a side elevation of the winding disk;

Fig. 9 is a diagrammatic view showing 55 the approximate position of the armature

before being driven by the impulser spring; and

Fig. 10 is a diagrammatic view of the approximate position of the armature after being driven by the impulser spring. 60

Like characters of reference designate like parts throughout the several views.

Referring to the accompanying drawings, I provide a winding and cushioning spring 1 mounted in a suitable annular housing 2. 65

Housing 2 is provided with suitable spaced projections 3 rigidly affixed to the housing, as shown in Fig. 4, which serve as stops for suitable buttons 4 against which the opposite ends of the coil spring 1 abut. The 70 spacing of the projections 3 to permit the stud or lug 7 to pass therebetween and which permits of the rotation of the member 7 subject to the action of the spring 1 not only provides for that action, but also facilitates 75 assembly of the winding disk for the tension of the spring is exerted against each side of the projections and permits of the easy insertion of the winding or driving stud 7 between the buttons 4 against which the 80 spring bears; and its equally easy removal without affecting the position of spring 1.

The housing 2 is preferably formed of sheet metal and is provided with suitable trips 5 oppositely arranged as shown in Fig. 5. I 85

provide a novel winding disk 6 having a stud or lug 7 of such size and shape as to admit of its insertion between the stops 3 and the buttons 4, whereby the winding disk may be actuated by the coil spring 1 which 90

is in operative engagement with the buttons 4, which are freely movable in the housing 2. Winding disk 6 is provided with suitable studs 7^a, oppositely positioned, on which 95

are pivotally mounted the dogs 8, each of which is provided with a projecting end 9 adapted to engage in the notched portion 10 of the cam 11 which is mounted on rear housing member 15. Armature shaft 14 is the standard taper magneto shaft, and to it 100

is keyed by key 11^a, the hub 12 of the winding disk 6. The impulser case or housing disk 2 is provided with suitable outer studs 13, preferably of the type known as an "Oldham coupling," but it is understood that any 105

other satisfactory type of coupling may be fastened to the housing or shell without departing from the principle employed. This shell or housing 2 constitutes the driving member of the impulser, that is, it is at- 110

tached to the drive shaft of the engine on which the magneto is installed, while an actuating part of the impulser—the hub of the winding disk—is rigidly attached to the 5 magneto armature shaft.

It is within the contemplation of my invention to make any suitable modification in the size and arrangement of the parts without substantially departing from the 10 principle of operation disclosed. Commonly, I employ two dogs 8, but one of these may be omitted when desirable.

The operation of the invention is as follows:

15 When the engine is turned over slowly the housing 2 rotates, and with it the winding disk 6 which is operatively connected with the housing by the stud 7. The dogs 8 which are carried by winding disk 6 are positioned 20 diametrically opposite each other, and as one of the dogs reaches the top side of the cam plate 11, which is rigidly mounted on the rear housing member 15 and frame 16, the projecting end 9 of the dog 8 falls into 25 the notched portion 10 of the cam plate 11, thereby arresting the rotation of the winding disk 6, and the hub 12 of the winding disk. As hub 12 is keyed to the magneto armature shaft 14 when the movement of 30 the winding disk is arrested the armature shaft is prevented from rotating, and this condition exists as long as the end of the dog remains caught in the notched portion 35 of the cam plate.

35 As the operation of the engine continues the engagement of the winding disk stud 7 with the buttons 4 that bear against the coil spring 1 causes the spring to be compressed 40 annularly until a trip 5 of housing 2 forces the dog 8 out of the notched portion 10 of cam plate 11, thereby releasing winding disk 6 and coil or winding spring 1 and causing 45 a rapid rotation of the armature shaft 14 which is keyed to the hub 12 of the winding disk 6. The armature of the magneto is thus rapidly rotated for a definite degree to a 50 stop within the impulser housing, but by providing the annularly arranged spring 1 a cushioning effect is obtained on the full 55 length of the winding spring. This construction gives the greatest winding space and the greatest cushioning effect. It also permits of either right or left hand operation without other changes except position-

55 ing the keyway, or timing to magneto. As will be understood by reference to the drawings, Figs. 2 and 4 particularly, the stud 7 of the winding disk is forced against one or the other of the buttons 4 and compresses 60 the spring in an annular direction, until the disk is suddenly released and instantly returned to normal position, the stud 7 striking against the head of the opposite button 4 and thus compressing the spring in that 65 reverse annular direction until the force of

impact has been totally absorbed. This action takes place with either a right hand or left hand winding or driving effort. As shown in the drawings the device is arranged to operate as a right hand impulser. 70 To operate the instrument in a left hand direction it would be necessary to reverse the angle of the trips 5 and readjust their location, but the operation would be the same, substantially. 75

What I claim is:

1. In an impulser for a magneto, the combination of impulser actuating means rigidly attached to the magneto armature shaft, a coupling housing operatively attached to the 80 drive shaft of the engine and a single winding and cushioning coil spring annularly disposed within the coupling housing and having its ends operatively bearing against a portion of the impulser actuating means 85 to afford a cushioning effect for the full length of the aforesaid spring.

2. In an impulser for a magneto, the combination of a circular housing adapted to be attached to the drive shaft of the engine, a 90 winding and cushioning coil spring annularly arranged within said housing, buttons against which the coil spring bears at its respective ends, and means rigidly attached to the magneto armature shaft in operative 95 engagement with the aforesaid buttons and spring, whereby the spring may exert a cushioning effect.

3. In an impulser for a magneto, the combination of a magneto armature shaft, a 100 winding disk keyed to said shaft, an impulser housing operatively connected to the drive shaft of the engine, a coil spring annularly arranged within said housing and having its 105 respective ends operatively bearing against a stud of the winding disk, the aforesaid stud affixed to the winding disk, one or more dogs pivotally mounted on the winding disk, a cam plate shaped to temporarily arrest the movement of the dogs, and one or more 110 trips on the rotatable housing adapted to periodically release the dogs and actuate the armature shaft subject to the cushioning effect of the above-described spring, the above-described disks and trips being 115 completely incased within the impulser housing, substantially as set forth.

4. In an impulser for a magneto, an annular housing having opposite spaced projections, in combination with a winding disk 120 comprising a hub portion having a key adapted to engage an armature shaft of a magneto, a disk portion, a stud projecting from the disk portion, said stud being freely movable between the aforesaid spaced projections of the annular housing, and one or more dogs pivotally mounted on the opposite side of the disk portion, for the purposes 125 described.

5. As a new article of manufacture, an 130

impulser housing having coupling elements on its exterior, the housing having a hub portion, a projection within the housing adapted to operate as an abutment member 5 for an annularly arranged spring, and one or more inwardly bent portions of the housing disposed at an angle to operate as a trip member for the purposes hereinbefore described.

10 6. In an impulser for a magneto, the combination of a magneto shaft, a winding disk keyed to said shaft, and having a stud, one or more dogs mounted on the winding disk, a stationary cam plate having a notched portion shaped to temporarily arrest the movement of the dogs and winding disk, an annular impulser housing operatively connected to the drive shaft of the engine, trips formed of a section of the housing adapted 15 to engage and release the dogs from the cam plate, an annularly disposed spring in the impulser housing, the housing having spaced projections between which a stud carried by the winding disk is freely movable, members interposed between the ends of the spring and the aforesaid stud, whereby the spring is operatively connected to the winding disk to take up the impact of the disk when its rotative movement is arrested.

20 7. In an impulser for a magneto, the combination of a housing adapted to be operatively connected to the drive shaft of the engine and shaped to protect the impulser mechanism from dirt and oil, a cushioning 25 and winding spring annularly arranged within said housing, movable buttons against which the ends of the aforesaid

spring bears, a winding disk operatively connected to the magneto shaft and, said winding disk having a projection positioned 40 between the aforesaid buttons, whereby the spring may exert a cushioning and winding effect.

8. In a device of the class described, the combination of a magneto armature shaft, a winding disk keyed to said shaft, a stud near the outer portion of the winding disk, an impulser housing operatively connected to the drive shaft of the engine and substantially incasing the impulser mechanism to 50 protect same from dust and oil, a spiral spring disposed in an annular chamber in said housing and having its ends in operative engagement with the stud on the winding disk, the impulser housing having one 55 or more inwardly projecting trips formed of a section of said housing, the impulser housing also having opposed spaced projections between which the stud of the winding disk is freely movable, one or more dogs 60 mounted on the winding disk, a cam plate adapted to temporarily arrest the movement of the dogs under predetermined conditions, substantially as described.

9. As a new article of manufacture, an 65 annular impulser housing shaped to substantially incase impulser mechanism to protect same from dust and oil, said housing having opposite inwardly extending spaced projections, and having one or more inwardly bent sections forming trips, substantially as shown.

HARLIE O. PUTT.
